No. 746,512.

PATENTED DEC. 8, 1903.

R. HÜBNER.

ELECTRIC RAILWAY.

APPLICATION FILED DEC. 19, 1902.

NO MODEL.

UNITED STATES PATENT OFFICE.

ROBERT HÜBNER, OF NEW YORK, N. Y.

ELECTRIC RAILWAY.

SPECIFICATION forming part of Letters Patent No. 746,512, dated December 8, 1903.

Application filed December 19, 1902. Serial No. 135,870. (No model.)

To all whom it may concern:

Be it known that I, ROBERT HÜBNER, a subject of the Emperor of Germany, and a resident of the borough of Manhattan, city, 5 county, and State of New York, have invented certain new and useful Improvements in Electric Railways, of which the following is a specification.

My invention relates to electric railways, 10 and particularly to those in which a so-called "third" rail is used as a conductor in connection with a shoe suspended from the car and adapted to take current from said conductor.

The object of my invention is to provide 15 protection for the said conductor against the action of the elements, and particularly against snow or sleet, while allowing the contact-shoe of the customary construction to be used.

20 Another object of my invention is to prevent accidents such as may occur by persons coming in contact with the live conductor.

To this end my invention consists in a particular novel construction of a sectional protector or cover for the conductor or third rail 25 and also in a particular device for temporarily moving the sections of the protector out of the way of the arm which carries the contact-shoe.

30 The invention will now be described with reference to the accompanying drawings, which illustrate two forms of my invention, and the features of novelty will then be pointed out in the appended claims.

35 Figure 1 is a plan of a third-rail construction having my invention applied thereto with parts in section. Fig. 2 is a side elevation of the same parts with some of the protector-sections in section. Fig. 3 is a cross-section on line 3 3 of Fig. 2. Fig. 4 is a detail showing a stop device for the protector different from that shown in Fig. 3. Fig. 5 is a plan of the second form of my invention; 40 and Figs. 6 and 7 are sectional elevations 45 thereof on lines 6 6 and 7 7, respectively, of Fig. 5.

In each of the constructions shown the third-rail conductor A is arranged between two beams B B', which extend above the top 50 of the rail and which are supported in any suitable manner, the third rail being usually located at a higher level than the adjacent

main or track rail C. On the conductor-rail A is adapted to slide a contact-shoe D, which is generally secured loosely to the car—as, 55 for instance, by means of links E—the lower ends of which are pivotally connected with the said shoe, while their upper ends have a similar connection with other links pivotally attached to an arm or bracket upon the car. 60 Thus the shoe will always ride on the third rail A notwithstanding any up-and-down movement of the car-body. So far the construction is substantially the usual one.

In order to protect the third rail against contact with living beings, as also against the detrimental action of the elements, and particularly of ice, snow, or sleet, I provide a protector or cover arranged to extend from one beam B to the other B', so that the rail A is 70 contained in a normally covered or closed conduit or chaanel. In the form of construction illustrated by Figs. 1 to 4 the sections F of the protector are hinged to one of the beams B, as indicated at F', so that they are capable 75 of swinging upwardly into a position such as indicated in Fig. 3, in which they leave a free path for the links E, as well as for the arm or bracket from which such links are suspended. In order to normally close the protector-sections F down upon the beam B', I may rely simply upon gravity, or a spring G may be used to start the protector-sections downward. Instead of this I may also simply provide a stop H, such as shown in Fig. 4, preventing the 85 protector-section from falling outward and causing it to return to its normal position as soon as it is allowed to do so.

It will be understood that some device has to be provided to lift the protector-sections 90 into the position indicated by Fig. 3 in advance of the links E or other supporting means of the contact-shoe D. This operating device for the protector-sections is connected with the contact-shoe, preferably in a 95 loose manner, so that the operating device and the shoe may to a certain extent move independently of each other. The connection may be effected by bolts E², extending through slots E³ E⁴. The operating device consists of 100 a plate-like body I, preferably apertured at I² for the passage of the links E, which support the shoe D and which is provided at one end or at both ends with a toe J, having a

surface beveled downwardly and adapted to project with its free lower end under the protector-sections F. To facilitate the engagement of the toe J with the protector-section, 5 the latter may be provided with notches F², as indicated in Fig. 2. It will be seen that the contact-shoe is located under the plate-like body I, which thus forms a cover and protector for the shoe. The body I is also 10 preferably so constructed as to act as a guide for the operating device, and for this purpose a lateral guiding extension I' is formed on said body or secured thereto, the said extension being arranged to overlap the beam B', so 15 that the beam is, as it were, received in a groove of the said operating device. Furthermore, the body I preferably rests and travels upon the top of both beams B B'.

It will be understood that proper care should 20 be used to prevent short circuits, and to this end it will be preferable to make the protector-sections F and the operating device I J of non-conducting material, or, if this is not advisable for mechanical reasons, to insulate 25 the said operating device from the contact-shoe. In operation the protector-sections F will normally extend in a horizontal position from one beam B to the other B', so as to cover the conduit which contains the 30 third rail A and to prevent the entrance of snow, ice, sleet, or other matter which might interfere with the proper making of a contact. Whenever during the travel of a car the toe J passes under one of the protector-sections F, such section will be gradually raised to the position shown in Fig. 3, so as 35 to be out of the way of the links E, or, generically speaking, of those parts which connect the contact-shoe and the operating device 40 with the car. These parts I have termed in the claims a "carrying-arm," and I desire it to be understood that such term is to be interpreted broadly as covering any suitable supporting connection from the car to the 45 contact-shoe or operating device. Similarly, I wish it to be understood that where I have used the term "contact-shoe" I desire to include under this term any suitable contact device. It will thus be understood that the 50 protector-sections F are opened or raised only where this is necessary for the taking of the current and that they drop back to their normal positions as soon as the car has passed.

In the form of construction illustrated by 55 Figs. 5, 6, and 7 the protector-sections f are arranged to move horizontally out of the path of the carrying-arm. For this purpose the said sections f are mounted to slide upon transverse guide-bars K and are normally 60 drawn by springs f', attached to brackets or hooks f³, into a position above the third rail A. The operating device has a body i, with a lateral guide member i' and beveled toes j arranged to engage cut-away surfaces f² on 65 the protector-sections f, although it is not necessary to cut away the corners of the protector-sections, as shown. The toes j are bevel-

eled from one side to the other instead of from top to bottom and are thus adapted to force the protector-sections sidewise instead of upward. The connection of the operating device with the carrying-arm may be similar to that shown in Figs. 1, 2, and 3. The operation of the second form of my invention will be substantially the same as that of the 75 first form, except that the protector-sections are moved laterally instead of upward to uncover the conduit.

I desire it to be understood that various modifications may be made without departing 80 from the nature of my invention.

While in the drawings I have shown the protector-sections F f provided with flat upper surfaces, I desire it to be understood that they may be given any desired shape, and 85 in some cases they may be curved or roof-shaped to facilitate the shedding of rain and the like. It will also be understood that while I have described the contact-shoe and the operating device as supported from the 90 car by the same carrying-arm such construction is not essential, as each of the said parts may have its own connection with the car.

What I claim, and desire to secure by Letters Patent, is—

1. The combination, with a conduit, a conductor and a protector therefor consisting of individually-movable sections, of a contact-shoe adapted to engage said conductor, and an operating device held to move with said 100 contact-shoe and arranged to shift the protector-sections from their normal position, said operating device being provided with a guide member arranged to engage the top of the conduit.

2. The combination, with a conductor, of beams arranged at each side thereof, a protecting-cover consisting of individually-movable sections adapted to extend from one beam to the other, a contact-shoe arranged 110 to engage the conductor, an operating device held to move with said contact-shoe and to shift the protector-sections from their normal position, said operating device being provided with a guide member in engagement 115 with the top of one of said beams.

3. The combination, with a conductor, of beams arranged at each side thereof, a protector consisting of individually-movable cover-sections arranged to extend from one 120 beam to the other, a contact-shoe arranged to engage the conductor, a carrying-arm for said contact-shoe, and an operating device through which extends said carrying-arm and which is arranged to move with the contact-shoe and to shift the protector-sections from their normal position, said operating device being arranged to rest and slide on the upper surfaces of both of said beams.

4. The combination with a conduit having 125 an open top, of a conductor arranged in said conduit, a contact-shoe arranged to engage the conductor, a protector consisting of individually-movable sections arranged to

cover the open top of said conduit, and an operating device arranged to travel upon the upper surface of the conduit and provided with means for shifting the protector-sections 5 out of their normal position.

5. The combination with a conduit, a conductor within the same, a sectional protector for said conduit, a contact-shoe arranged to engage the conductor, and an operating device 10 vice arranged to travel upon the top of the

conduit and to move the protector-sections out of their normal position.

In testimony whereof I have signed my name to this specification in the presence of two subscribing witnesses.

ROBT. HÜBNER.
